VALVE.

1,385,137.

Specification of Letters Patent. Patented July 19, 1921.

Application filed August 22, 1919. Serial No. 319,048.

To all whom it may concern:

Be it known that I, GEORGE J. KAUFFMANN, a citizen of the United States, residing at Easton, in the county of Northampton and 5 State of Pennsylvania, have invented certain new and useful Improvements in Valves, whereof the following is a specification, reference being had to the accompanying drawings.

10 My invention relates to valves such as are used in the suction and discharge of pumps handling various kinds of fluids. It is my aim to improve the wearing qualities and action of such valves and of the associated 15 parts; to make it possible for pumps to operate with less leakage and higher available capacity; to reduce the renewal expense; and to lengthen the intervals between necessary 20 shut downs. Other advantages obtainable in connection with my invention will appear from the description hereinafter of the best forms of embodiment at present known to me, while its real scope and essence will be indicated in my claims.

25 Heretofore, pump valves have been made principally of one material and in one single form: that is to say, of rubber in the shape of a disk flat on both sides and quite thick and heavy. Such valves erode irregularly 30 under the conditions of use, and very soon leak excessively, which greatly diminishes the efficiency and output of the pump. The valves wear out very quickly,—often in from one to ten days,—which involves heavy 35 renewal expense and frequent and far more costly and annoying shut-downs for renewals. Efforts at improvement have, in general, been in the direction of employing metal reinforcement for stiffening the rubber body or seating surface of the valve, or 40 else of substituting various fiber or mineral compositions for rubber as a valve-material,—but without departure from the thick, heavy, flat form. Such efforts have, 45 however, brought but trifling improvements; and the wear of such valves is greatly aggravated by variations of temperature over wide ranges, and by drying out of the valves 50 when the pumps are not continuously operated. Occasional attempts to employ essentially different materials or any other than the thick, flat, heavy disk form have been equally futile in a practical way.

I have discovered that all these defects 55 can be overcome by radical departure from

accepted practice as regards both the material and the form of the valve: that is, by making the valve of metal and so thin as to be very light as compared with the valves described above. The benefits of this radical 60 change can be considerably enhanced by such a design of the sealing parts of the valve structure,—the movable member or valve proper and its seat,—that they shall come in contact only over a relatively narrow 65 zone, and also by rounding or otherwise suitably “reducing” the edges of the valve member past which the water flows when the valve is opening and closing. While the narrow zone of contact can be secured in various 70 ways, the most advantageous is by forming the valve member with outstanding portions which reinforce and stiffen it, and whose tops or crests constitute the contact surfaces of said member. This can best be 75 done by making the valve of sheet metal and suitably embossing it, as by a stamping, pressing, or spinning operation. It is also of advantage that the outer contact zone portions of the valve disk or member re- 80 cede sharply, on both sides, from the contact zones at their tops.

In the drawings, Figure I, shows a valve assembly with a valve embodying my invention, certain parts being in axial sec- 85 tion.

Fig. II, is a plan view, certain upper parts being broken away and removed.

Fig. III, is a perspective view of a modified form of valve in axial section.

The valve assembly shown in Figs. I and II, is of an ordinary type, comprising a seat structure 1 screwed into the wall 2 of the pump chamber and having a rim 2¹, radial webs 3, and a central hub 4. Into the hub 95 4 is screwed a stud 5 that serves as a guide member for the valve and carries a flanged and fluted head 6 that fits within and affords an abutment for the helical compression spring 7, which urges the valve member 8 to its seat. Thus the mounting for the valve 8 is of the ordinary commercial type. The valve 8 itself, however is not of usual type, but, on the contrary, consists of a sheet metal disk centrally apertured to 100 slide freely but rather closely on the guide stud 5, and annularly embossed, at 10 and 11, to afford narrow outstanding contact zones for engaging and coacting with the inner and outer flat annular seats or seating 105 110

surfaces 12 and 13 of the structure 1. As shown, these annular embossings are adjacent the inner and outer edges 14 and 15 of the valve disk 8, whose curved surfaces 5 (here formed as an incident of the embossing operation) spring directly from them, and recede sharply from the seating face of the disk 8. These edge surfaces have the final direction, approximately, of the water 10 flowing past them, as it leaves them, so as to offer minimum resistance and sustain minimum wear and scouring effect. The inner edge, especially, is well rounded, and is flanged inward away from the contact face 15 of the disk,—both for the purpose just mentioned and to facilitate free rocking of the loose valve on its guide member 5 and its seat.

The embossing of the metal disk 8 to form 20 the outstanding contact zones strengthens it to such an extent as to permit it to be made much thinner and lighter than would otherwise be consistent with a proper degree of stiffness and ruggedness. The thinness of 25 the valve also affords a highly desirable flexibility and resiliency under the working pressure to which it is subjected in the operation of the pump. In order to prolong the life of the valve as much as possible, it 30 may advantageously be made of non-oxidizing metal.

Fig. III, shows a slightly modified form of valve suitable for large sizes,—such as 12 to 18 inches in diameter or more. As here 35 shown, the body of the valve member between its inner and outer contact zones is reinforced and rendered more rigid by means of radially extending ribs 16 embossed to slightly less height than the contact zone 40 embossments.

The great strength of my valve in either form and its light weight permit rapid and quick action at high pressures with minimum shock, thus reducing wear on the valve 45 and valve seats and greatly prolonging their life. Wear is also minimized by the narrowness and rounding of the seating zones and the resultant reduction of the tendency for grit to lodge at these points. Its strength 50 and stiffness also allow direct support by contact with the radial webs 3 to be dispensed with, which tends to eliminate sticking and promotes free flow of the liquid being pumped. Its elasticity and flexibility 55 and the outstanding of its seating surfaces from its main body portion permit it to seat and seal tightly on old seat structures where the inner and outer seats have been worn down to different levels,—and this even 60 when the seats are worn down below the tops of the radial webs connecting the inner and outer seats. The fact that the crests of the contact zones afford the sole sealing with the corresponding flat valve seats and its 65 entire freedom of self adjustment to the full

extent permitted by its resiliency and flat form also favor tight sealing under all conditions. The annular reinforcement and stiffening of the inner and outer edges of the valve 8 by its outstanding annular contact zone portions 12 and 13 prevents the valve from being bent out of shape and so ruined by the pressure and momentum of the water when pieces of foreign material lodge under it. The sharp recession of the 75 contact zone portions 12 and 13 from the contact zones at their tops greatly contributes toward minimizing the tendency for foreign matter or dirt to lodge beneath them.

The extreme thinness permits maximum 80 valve opening and greatly diminishes the suction required to lift the valve, and this thinness and the narrowness of the contact zone at the central valve aperture also greatly reduce the tendency for dirt or grit 85 to lodge and stick at this point and wear the valve aperture larger, so as to bring about a condition of excessive leakage. The lightness of the valve permits its use in horizontal, inclined, or vertical positions with 90 equal efficiency, and it also permits rocking motion of the valve around the stud 5, so as to give a quick action under light suction.

The making of the valve of metal obviates 95 the necessity for pump users to carry in stock valves of various compositions and change them when different liquids (such as water, oil, acid, alcohol, etc.,) are pumped, or when the temperature or pressure of the liquid varies, since the metal employed may be non-oxidizing and anti-corrosive or acid-resistant. All the parts of the valve assembly 100 may be made of the same metal, so as to minimize electrolytic action.

To give an idea of the possible lightness and utility of my type of valve, I may cite the fact that a valve $4\frac{1}{2}$ " in outside diameter of metal $\frac{1}{16}$ " thick may weigh less than 5 ounces, and will give many months or even a year or more of satisfactory, efficient, continuous service.

Having thus described my invention, I claim:—

1. The combination of a pump valve seat with inner and outer annular seat surfaces; a guide member; and a thin, light guide-apertured metal disk valve for said seat reinforced and stiffened with outstanding annular contact zone portions for coacting with the aforesaid annular seat surfaces; said valve being loose on said guide member and free to rock with reference thereto and to its seat.

2. The combination of a pump valve seat with inner and outer annular seat surfaces; a guide member; and a thin, light guide-apertured metal disk valve for said seat with inner and outer edges annularly reinforced and stiffened and receding sharply from its seating face; said valve being loose on said 130

- guide member and free to rock with reference thereto and to its seat.
3. The combination of a pump valve seat with inner and outer annular seat surfaces; 5 a central guide member; and a thin, light guide-apertured metal disk valve for said seat reinforced and stiffened with outstanding annular contact zone portions that recede sharply on both sides from the contact 10 zones at their tops and coact with the aforesaid annular seat surfaces; said valve being loose on said guide member and free to rock with reference thereto and to its seat.
4. The combination of a pump valve seat 15 with inner and outer annular seat surfaces; a guide member; and a thin, light guide-apertured metal disk valve for said seat having its outer edge reinforced and stiffened with an outstanding annular contact zone portion 20 that recedes sharply on both sides from the contact zone at its top and coacts with the aforesaid outer annular seat surface, and its inner edge also annularly reinforced and stiffened; said valve being loose on said 25 guide member and free to rock with reference thereto and to its seat, and its inner edge being rounded from the seating face of the valve to facilitate such rocking.
5. A thin, light metal pump valve, adapted 30 to rock freely with reference to the guide and seat of a pump mounting, and consisting of a metal disk reinforced and stiffened at its outer edge with an annular outstanding contact zone portion that recedes 35 sharply on both sides from the contact zone at its top.
6. A thin, light metal pump valve, adapted 40 to rock freely with reference to the guide member and seat of an ordinary commercial pump valve mounting, and consisting of a guide-apertured metal disk reinforced and stiffened with outstanding annular contact 45 zone portions for coacting with the inner and outer annular seat surfaces of an ordinary commercial pump valve seat.
7. A thin, light metal pump valve, adapted 50 to rock freely with reference to the guide member and seat of an ordinary commercial pump valve mounting, and consisting of a 55 guide-apertured metal disk with inner and

outer edges annularly reinforced and stiffened and receding sharply from its seating face, the receding inner edge being rounded so as to facilitate rocking of the valve about a guide member.

8. A thin, light metal pump valve, adapted 55 to rock freely with reference to the guide member and seat of an ordinary commercial pump valve mounting, and consisting of a guide-apertured metal disk reinforced and stiffened with outstanding annular contact 60 zone portions that recede sharply on both sides from the contact zones at their tops and are adapted to coact with the inner and outer annular seat surfaces of an ordinary 65 commercial pump valve seat.

9. A thin, light metal pump valve, adapted 70 to rock freely with reference to the guide member and seat of an ordinary commercial pump valve mounting, and consisting of a guide-apertured sheet metal disk reinforced and stiffened at its outer edge with an embossed outstanding annular contact zone 75 portion that recedes sharply on both sides from the contact zone at its top, and annularly reinforced and stiffened at its inner edge by rounding and flanging inward of said edge away from the contact face of the disk so as to facilitate rocking of the disk with reference to said member.

10. A thin, light metal pump valve, adapted 80 to rock freely with reference to the guide member and seat of an ordinary commercial pump valve mounting, and consisting of a guide-apertured sheet metal disk reinforced and stiffened with inner and outer outstanding 85 annular embossed contact zone portions that recede sharply on both sides from the contact zones at their tops and are adapted to coact with the inner and outer annular seat surfaces of an ordinary commercial 90 pump valve seat.

In testimony whereof I have hereunto signed my name at Philadelphia, Pennsylvania this fourteenth day of August, 1919. 95

GEORGE J. KAUFFMANN.
